TO THE O. M. EDWARDS COMPANY INC., OF SYRACUSE, NEW YORK, A CORPORATION
OF NEW YORK

WEATHER STRIP CONSTRUCTION FOR WINDOW FRAMES AND SASHES

Application filed January 21, 1930. Serial No. 422,456.

This invention relates to window frame and sash constructions and has for its object a particularly simple and efficient weather strip construction for sealing the window against the inlet of air drafts, particularly windows for vehicles as railway cars, motor busses and the like. The particular object of this invention is a weather strip carried by the window guide or frame and coacting with the edge and the outer face of the sash members or stiles to seal the sash against the inlet of air drafts at two points, that is, at its edge and outer face adjacent the window guide or frame.

The invention consists in the novel features and in the combinations and constructions hereinafter set forth and claimed.

In describing this invention, reference is had to the accompanying drawings in which like characters designate corresponding parts in all the views.

Figure 1 is a fragmentary vertical sectional view of a window sash and frame embodying our invention.

Figure 2 is an enlarged transverse, fragmentary, sectional view through the window sash and frame.

Figure 3 is a view similar to Figure 1, parts being omitted and the sash being shown as displaced slightly showing the normal position of the weather strip members or flanges before being compressed by the sash.

1 designates, generally, the frame, and 2, the sash. The frame 1 may be of any suitable form, size and construction, and it is here shown as made up of a sheet metal body 3 mountable in a window opening of a railway car.

4 designates the sheeting of a railway car. The body 3 is shaped to form an outer window stop 5. 6 designates an inner stop, which may be of wood or metal, the inner stop being secured to the body 1. The outer stop 5 and the inner stop 6 together with an intermediate portion of the body 1 form a channel 7 which constitutes a guide for the sash 2 or the stile thereof.

This invention comprises, generally, a weather strip means carried by or within the guide and coacting with the sash to seal

the outer side of the sash adjacent the guide and the inner edge of the sash in the guide against the inlet of air drafts, this weather strip means including a sheet metal flange following generally the interior angle toward the outer side of the channel and a sheet metal flange lapping the margin of the outer face of the sash and extending outside of the channel and provided with an angular flange extending at an inclined angle toward and engaging at its end with the top face of the stop 5, and forming a deflector for deflecting air drafts away from the sash. More specifically, the weather strip means comprises a carrier 8 and sheet metal weather strip flanges carried by the carrier, one located in the channel to engage the edge of the sash and the other extending outside of the channel to engage the margin of the front face of the sash and also the top face of the outer stop 5.

The carrier 8 is here shown as an angle iron nested in the angle of the channel toward the outer stop and secured thereto in any suitable manner as by screws 9. The flange 13 of the carrier against the stop 5 extends inwardly beyond the stop.

10 and 11 designate respectively, the flanges of a sheet metal weather strip, which strip has a bearing on and is preferably secured along its median line as at 12 to the carrier 8, it being usually welded at 12 along its median line to the carrier 8. The flange 10 extends in a general direction following the angle of the carrier or the channel and is tensioned, as seen in Figure 3, to normally stand away from the carrier, it being formed with a reversely bent loop portion 14 extending toward the edge of the sash to coact therewith so as to be compressed by the sash obliquely toward the angle of the carrier 8 or toward the outer stop. The loop 14 and the sash have coacting means which tends to compress the strip 10 in an oblique direction toward the angle of the carrier and the angle of the guide toward the stop 5.

As here illustrated, the sash is formed with a beveled or cam face 15 coacting with the end portion of the loop 14.

The flange 11 of the weather strip is also

tensioned to press against the outer face of the sash, that is, it normally stands away from the underlying flange 13 of the carrier 8. This flange 13 extends outside of the channel, that is, beyond the top wall of the outer stop 5. Usually, the sash or the stile thereof is provided with a rabbet 17 for receiving the flange 13 and the weather strip flange 11. The flange 11 is also formed with a reverse-bent portion 18 extending over the outer edge of the flange 13 of the carrier 8 and at an inclined angle outwardly toward the top wall of the outer stop 5 and engaging at 19 with said top wall. It is usually formed with a bead 20 for engaging the top wall of the outer stop 5. This portion 18 forms a deflector for deflecting the air drafts outwardly away from the sash so that they will have a minimum tendency to force their way into the channel through the rabbet 17. Also, the bend 21 between the major part of said weather strip 11 and the portion 18 coacts at 22 with the end wall 23 of the rabbet and during the compression of this flange 11, the bend 21 has a slight movement toward the end wall 22 of the rabbet due to the fact that the bend is swinging about an axis or fulcrum 12 and the bead 20 of the portion 18 is held from swinging inwardly while it is sliding outwardly along the top of the outer stop 5.

The sash is provided with the usual sash holders there being usually two sash holders at the lower corners of the sash, each of these sash holders including a member as a bolt which coacts with means as a rack on the inner stop, the bolt and the rack coacting to thrust the sash toward the outer stop and hence hold the weather strip member 11 in snug engagement with the sash or with the wall of the rabbet 17.

The sash holders may be of any suitable form, size and construction and include a casting 24 having a spring-pressed bolt 25 slidable therein which is operable by a movable lever 26. As before stated, the sash holder may be of any suitable construction and as sash holders of this type are well known, further description thereof is thought to be unnecessary.

27 designates the rack on the inner stop, the bolt 25 and the rack 27 having coacting bevelled surfaces which act inclined plane fashion to thrust the sash toward the outer stop and hence compress the weather strip 11 and particularly the portion 13 thereof so that it makes snug engagement with the wall of the rack 27. The formation of the bolt and the rack to act inclined plane fashion per se is not part of this invention, but the cooperation or combination of the sash holder and rack acting to thrust the sash toward the outer stop with the weather strip in such a manner that the action of the sash holder holds the weather strip in snug engagement

with the sash and is a feature of the invention.

Owing to the fact that this weather strip is a unitary structure and is carried by the window guide, it is readily applied to standard forms of guides for railway window sashes and furthermore as it coacts with the sash at the edge and front sash thereof, the sash is sealed at two points against the passage of air drafts. Owing to the deflector portion 18, air drafts which would otherwise normally tend to force through the guide or around the edge of the sash are deflected away from the sash. It will be understood that there is a weather strip at both edges of the sash. Owing to the weather strips, the sashes are snugly mounted regardless of slight variations either in the width of the sashes or in the width of the frames or the distance between the guides. It will be understood that such variations in regard to guides are always present and this weather strip compensates for variations, within limits, in the distance between the guides, that is, the guides at opposite edges of the sash.

What we claim is:

1. The combination with a window sash and guide therefor, in the form of a channel angular in cross section, of weather strip means carried by the guide and extending into the channel, including a resilient strip located in the channel, the strip and the sash having coacting means forcing the strip toward the outer side and the bottom of the channel in an oblique direction.

2. The combination with a window sash and guide therefor, the guide being in the form of a channel angular in cross section, of weather strip means carried by the guide and including a resilient sheet metal strip member having a flange arranged to lap the margin of the outer side of the sash and a second flange angular with the first and extending crosswise of the edge of the sash, the latter flange having a loop portion for coacting with the edge of the sash to be engaged and compressed thereby.

3. The combination with a window sash and guide therefor, the guide being in the form of a channel angular in cross section, of weather strip means carried by the guide and including a resilient sheet metal strip member having a flange arranged to lap the margin of the outer side of the sash and a second flange angular with the first and extending crosswise of the edge of the sash, the latter flange having a loop portion for coacting with the edge of the sash to be engaged and compressed thereby, the sash being formed with a rabbet for receiving the former flange and the former flange having means for sealing the joint against air drafts at the end wall of the rabbet.

4. The combination with a window sash,

- inner and outer stops forming a guide for the sash, the sash being formed with a rabbet in the side thereof toward the outer stop, of weather strip means carried by the guide and including a resilient flange arranged to extend into the rabbet, said flange having an angular portion extending outwardly and at an inclined angle toward the top face of the outer stop forming a deflector. 5
- 10 5. The combination with a window sash and inner and outer stops forming a sash guide, the sash being formed with a rabbet in the side thereof toward the outer stop, of weather strip means carried by the guide and including a resilient flange arranged to extend into the rabbet, said flange having an angular portion extending outwardly and at an inclined angle toward the top face of the outer stop forming a deflector, the angle 15 between said flange and the angular portion coacting with the end wall of the rabbet to seal the rabbet against the inlet of air drafts. 20
6. The combination with a window sash and inner and outer stops forming a sash 25 guide, a weather strip means comprising a carrier angular in cross section and nested in the interior angle of the guide toward the outer stop and a resilient strip carried by the carrier and coacting with the edge and 30 the margin of the outer face of the sash. 7. The combination with a window sash and inner and outer stops forming a sash 35 guide, of weather strip means comprising a carrier angular in cross section and nested in the interior angle of the guide toward the outer stop and a strip carried by the carrier and coacting with the sash. 40
8. The combination with a window sash and inner and outer stops forming a sash 45 guide, of a carrier located in the interior angle of the guide toward the outer stop, of a sheet metal weather strip carried by the carrier and bearing at its intermediate portion against the same, the portion of the strip on 50 the opposite sides of its bearing point constituting two weather strip flanges, one of said flanges following generally the angle of the carrier and having a reversely bent portion for engaging the edge of the sash, the 55 portion of the weather strip member, on the other side of its bearing, being tensioned to press against the inner margin of the outer face of the sash and having an outwardly extending portion extending at an inclined angle outwardly and pressing against the top face of the outer stop. 60
9. The combination with a window sash and inner and outer stops, of a carrier located in the interior angle of the guide toward the 65 outer stop, of a sheet metal weather strip carried by the carrier and bearing at its intermediate portion against the same, the portion of the strip on the opposite sides of its bearing point constituting two weather strip flanges, one of said flanges following generally the angle of the carrier and having a reversely bent portion for engaging the edge of the sash, the portion of the weather strip member, on the other side of its bearing, being tensioned to press against the inner margin of the outer face of the sash and having an outwardly extending portion extending at an inclined angle outwardly and pressing against the top face of the outer stop, the sash being formed with a rabbet for receiving the latter flange and the bend of the latter flange coacting with the end wall of the rabbet to seal the rabbet against the inlet of air drafts. 70
10. The combination with a window sash and frame having a sash guide, of weather strip means carried by the guide and engaging the outer face of the margin of the sash adjacent the guide, a sash holder carried on the inner face of the sash and having a movable locking member coacting with means on the frame to hold the sash from movement, said member and the means on the inner stop coacting to thrust the sash outwardly toward the outer stop and hold the said weather strip means and the outer side of the sash in snug engagement. 80
- In testimony whereof, we have hereunto signed our names, at Syracuse, in the county of Onondaga, and State of New York, this 3rd day of January, 1930. 85
